THE ELECTRIC AUTO-LITE COMPANY, OF TOLEDO, OHIO, A CORPORATION OF OHIO

COIL CONSTRUCTION

Application filed July 20, 1928. Serial No. 294,143.

This invention relates to induction coils and particularly to coils of the high tension discharge type such as are used in ignition systems for internal combustion engines and in the operation of high frequency apparatus. It is well known in the art that in devices of this character, an interrupted or alternating current in a primary winding of comparatively few turns is stepped up or increased into a current of greatly amplified voltage by means of a secondary winding of many turns. In the production of an efficient induction coil of this character, it is necessary to concentrate the wire of the secondary winding into a small compass so as to position practically all or at least the greater part of it inside the magnetic field of the primary winding and core. This construction necessarily places a limit upon the amount of insulation which can be used between the juxtaposed layers and between the adjacent turns in the same layer. Another condition which is to be encountered lies in the fact that if an insulation of high specific inductive capacity be employed, the result is to amplify to an alarming factor the condenser effect between the successive layers of wire.

We have found that during the operation of the coil of this character there is superimposed upon the ordinary and generally described secondary action, a static surging effect wherein the amount of electricity involved is extremely small, but its electro-motive force comparatively high. This effect reaches a maximum value or intensity in the region adjacent the extremities of the secondary coil structure. The effect of this high potential static charge appears to seek a path through the insulation after which the direct secondary discharge of greater quantity of lower potential is enabled to pass with its well known heating and disintegrating effect. In a coil wound in the normal manner, the insulation adjacent the extremities of the secondary winding is none too high between the adjacent layers; and break downs, burning or puncturing of the insulation usually occurs at these points.

This invention contemplates the utilization of novel means for preventing a puncturing

or breaking down of the insulation without enlarging the size of the coil structure and the invention comprehends the spacing of certain layers of wire, and maintaining the amount of insulation between the successive layers substantially uniform whereby the electric stresses are decreased and the condenser effect between the several layers of wire is substantially reduced.

The invention has for a further object to provide a coil structure of this character wherein the elements of the coil per se are compactly assembled, forming a very efficient and inexpensive structure.

Further objects and advantages are within the scope of this invention such as relate to the arrangement, operation and function of the related elements of the structure, to various details of construction and to combinations of parts, elements per se, and to economies of manufacture and numerous other features as will be apparent from a consideration of the specification and drawing of a form of the invention, which may be preferred, in which:

Figure 1 is a vertical, longitudinal, sectional view through the coil of our invention;

Figure 2 is a detail sectional view taken substantially on a line 2—2 of Figure 1;

Figure 3 is an enlarged fragmentary detail view of a portion of the coil structure;

Figure 4 is an enlarged fragmentary detail view of a portion of the coil structure showing the method of securing the leads to the windings.

We have shown our invention as embodied in an ignition coil suitable for use in the ignition system of an internal combustion engine, but it is to be understood that we do not wish to limit our invention to the particular embodiment illustrated, and that we contemplate the use of our invention wherever the same may be found to be applicable.

Referring more particularly to Figure 1, the coil structure comprises a laminated core 5 which is formed by assembling a plurality of iron or steel strips into a compact structure which is subsequently inserted into tubes 6 and 8 of suitable insulating material, the

tubes 6 and 8 being surrounded by a second insulating tube 7. Surrounding the tube 7 is a secondary winding 9, the construction of which will be hereinafter described in further detail.

Surrounding the secondary winding 9 is an insulating tube 11 upon which is wound a primary winding 12 superposed upon the secondary winding as shown in Figure 1. 10 Surrounding the primary winding 12 is another insulating tube 14, the complete winding and core assembly being supported and housed within a cylindrical metallic casing 16. Interposed between the insulating tube

14 and the walls of the casing 16 is a plurality of metallic laminations 17 which are assembled as shown in detail in Figure 2. These laminations serve to form a path for the magnetic lines of force set up in the core and 20 windings thus making a very efficient structure. The several laminations 17 are of semi-cylindrical form, the ends being slightly separated to form a gap which serves to decrease or reduce eddy currents.

25 One end of the core 5 is received into a bore in a supporting member 18 which may be of any suitable insulating material as, for example, porcelain which possesses high insulating qualities. One end of the casing 16 30 is adapted to be enclosed by means of a circular cover 20.

The other end of the casing 16 is enclosed by means of a metallic cap 22 which may be secured to the casing in any suitable manner 35 as by soldering illustrated at 23, the crown of the cap being provided with an enlarged bore which receives a member 24 of porcelain or other insulating material, the inner end of said member having a frusto-conical bore 40 which receives and supports the other end of the magnetic core structure 5. The outer extremity of the porcelain member 24 is provided with a bore 26 which contains a metallic thimble 27 forming the high tension terminal 45 for the secondary winding, the thimble being connected to one end of the winding by means of a lead 29.

We have found that in order to prevent a derangement or loosening of the wire of the 50 secondary winding it is desirable to pass the lead 29 through a small aperture in the outer insulating tube 7 surrounding the core 5 as particularly shown in Figure 4, the lead passing between the adjacent ends of the tubes 55 6 and 8. This arrangement serves as holding means for the end of the wire at the beginning of the winding operation and also tends to prevent an accidental breaking of the winding lead.

60 Positioned on either side of the porcelain member 24 are the primary terminals 30 and 31 connected to the respective ends of the primary windings by means of leads 32 and 33. The terminals 30 and 31 are provided 65 with threaded tenons 35 which are adapted

to pass through enlarged openings in the cap 22, the tenons being spaced from the edges of the opening and with the use of insulating washers 36 positioned on either side of the cap 22 a metallic connection between the terminals 30 and 31 and the cap 22 is avoided. 70

The coil structure is assembled before placing the cap 22 in position and any remaining cavities are filled with an insulating compound 37 which is impervious to moisture 75 and which serves as an additional means to prevent derangement of the parts in the casing. The cap 22 may be soldered or otherwise fixedly secured to the casing 16.

The secondary winding structure will now 80 be described in further detail. In the beginning of the operation of winding the secondary coil upon the tube 7, the first few layers of wire 40, preferably three or four, are so arranged that the individual turns or 85 convolutions of wire are spaced one from the other whereby fewer number of turns are enclosed in the space occupied by the winding per se, the several layers of wire being separated by suitable insulating strips. The remaining layers of wire, with the exception of the outermost three or four layers of the secondary winding, are "close" wound, i. e. the individual convolutions are substantially 90 in contact with each other. The outer layers 95 of wire are spaced similarly to the inner layers of wire, the several layers being separated by means of suitable strips of insulating material. It is to be understood that all the 100 layers of wire are insulated one from the other and in the form shown, substantially the same amount of insulating material is used between each successive layer irrespective of whether the wire is "close" wound or "space" wound.

We have distributed the dielectric stresses produced by high inductive effects and oscillating currents close to the magnetic core by spacing the turns or convolutions of the innermost and outermost layers of the secondary winding whereby a material saving is effected in the copper wire and insulating material used in the winding. 105

We have found it desirable in order to produce a coil of high efficiency, to decrease the 110 number of turns in each successive layer in the primary winding, however, the several layers of the primary winding may be wound with an equal number of turns which does not materially interfere with the successful 115 operation of the coil.

It is apparent that, within the scope of the invention modifications and different arrangements may be made other than is herein disclosed, and the present disclosure is illustrative merely, the invention comprehending all variations thereof. 120

What we claim is:

1. In a coil structure of the character disclosed comprising a core structure formed of 125

- a plurality of flat metallic strips; insulating means surrounding said core; primary and secondary windings superposed upon said core structure; a metallic casing surrounding said core and windings; a plurality of semi-cylindrical metallic laminations interposed between said casing and said windings; a metallic cap for said casing; said metallic cap having an insulating member centrally disposed thereof; a metallic element carried by said insulating member and forming a terminal for one of said coils; and a pair of coil terminals insulatingly supported upon said metallic cap.
2. In an ignition coil of the character disclosed comprising a core structure; insulating means surrounding said core, primary and secondary windings superposed upon said core structure, said secondary winding comprising a plurality of layers of turns of wire; uniform insulation between said layers; the turns of wire being closely wound in the central layers of said winding and, spaced apart at the beginning and end layers thereof as means for preventing a charge of high potential static from causing breakdown in said insulation; a casing surrounding said core and windings; a plurality of laminations between said windings and said casing; a cap for said casing, said cap supporting the terminals for the ignition coil.
3. In a coil structure of the character disclosed comprising a laminated core structure; insulating means extending longitudinally of and surrounding said core; an insulating member having a recess into which one end of said core extends; primary and secondary windings superposed upon said core structure, said secondary being inside said primary and said core extending beyond the ends of said windings; said secondary winding comprising a plurality of layers of turns of wire; insulation between said layers; means associated with an end layer of said secondary winding for preventing a charge of high potential static from causing breakdown in said insulation; a casing surrounding said core and windings; a curved structure between said windings and said casing arranged to prevent eddy current formations; a cap for said casing; an insulating member for the other end of said core having a recess into which said core extends; a metallic element carried by said insulating member constituting a terminal for one of said windings; and a pair of coil terminals insulatingly supported upon said cap and insulating compound filling the remaining voids at either end of said coil.
4. In a coil structure of the character disclosed comprising a core structure; insulating means surrounding said core, primary and secondary windings superposed upon said core structure, said secondary winding comprising a plurality of layers of turns of wire;
- insulation between said layers extending beyond said windings; the turns of wire being closely wound in the central layers of said winding and spaced apart at the beginning and end layers thereof; means associated with an end layer of said secondary winding for preventing a charge of high potential static from causing breakdown in said insulation; a casing surrounding said core and windings; a plurality of laminations between said windings and said casing; a cap for said casing; said cap having an insulating member for said core; a metallic element carried by said insulating member constituting a terminal for one of said windings; and a pair of coil terminals insulatingly supported upon said cap.
5. In a coil structure of the character disclosed comprising a core structure; insulating means surrounding said core; a secondary winding superposed upon said core structure; a primary winding superposed on said secondary winding; said secondary winding comprising a plurality of layers of turns of wire; insulation between said layers; means associated with an end layer of said secondary winding for preventing a charge of high potential static from causing breakdown in said insulation; a casing surrounding said core and windings; a plurality of semi-circular curved separate laminations shaped to fit around said primary winding and located between said winding and said casing; means to prevent eddy current formations in said laminations; a cap for said casing; said cap having an insulating member for said core; a metallic element carried by said insulating member constituting a terminal for one of said windings; and a pair of coil terminals insulatingly supported upon said cap.
6. In a coil structure of the character disclosed comprising a core structure; primary and secondary windings superposed upon said core structure said windings being shorter than said core, said secondary winding comprising a plurality of layers of turns of wire; insulation between said layers; means associated with an end layer of said secondary winding for preventing a charge of high potential static from causing breakdown in said insulation; insulation tubing surrounding the core structure which extends beyond said winding, said tubing also extending into the said winding structure; a casing surrounding said core and windings; a plurality of laminations between said windings and said casing; a cap for said casing, said cap having an insulating member for said core; a metallic element carried by said insulating member constituting a terminal for one of said windings; and a pair of coil terminals insulatingly supported upon said cap.
7. In an ignition coil of the character disclosed comprising a core structure; insulat-

- ing means surrounding said core; primary and secondary windings superposed on said core structure insulated therefrom, said secondary winding comprising a plurality of 5 layers of turns of wire; sheet insulation between said layers; means for preventing a charge of high potential static from causing break down in said insulation; a casing surrounding said core and windings; metallic 10 sheet material between said windings and said casing forming an outer magnetic field; a cap for said casing, said cap supporting the terminals for said coil; and means for securing the cap to said casing.
- 15 8. In a coil structure of the character disclosed comprising a core structure; insulating means extending longitudinally of and surrounding said core; an insulating member having a recess into which one end of said 20 core extends; primary and secondary windings superposed upon said core structure, said secondary winding being inside said primary winding and comprising a plurality of layers of turns of wire; insulation between 25 said layers; means associated with an end layer of said secondary winding for preventing a charge of high potential static from causing break down in said insulation; a casing surrounding said core and windings; a 30 curved structure between said windings and said casing arranged to prevent eddy current formations; an insulating member adjacent to the other end of said core having a recess into which said core extends; a metallic element 35 carried by said insulating member constituting a terminal for one of said windings; a plurality of coil terminals adjacent to said metallic element and insulated therefrom; and insulating compound filling the 40 voids between the elements of the coil assembly.
9. In a coil structure of the character disclosed comprising a magnetizable core structure; primary and secondary windings superposed upon said core structure insulated therefrom, said secondary winding comprising a plurality of layers of turns of wire; insulation between said layers extending beyond said windings; means associated with 45 an end layer of said secondary winding for preventing a charge of high potential static for causing break down in said insulation; a casing surrounding said core and windings; sheet material between said windings and said casing; a cap for said casing said cap having an insulating member provided with a terminal for said coil and extending within the casing adjacent said layers of insulation; and a plurality of coil terminals 55 supported upon said cap.
10. In a coil structure of the character disclosed comprising a core structure; insulating means surrounding said core; a secondary winding superposed upon said 60 core structure; a primary winding super- 11. In a coil structure of the character disclosed comprising a core structure; primary and secondary windings superposed upon said core structure; said windings being shorter than said core, said windings comprising a plurality of layers of turns of wire; insulation between said layers; means associated with an end layer of said secondary winding for preventing a charge of high potential static from causing break down in said insulation; tubing surrounding the core structure insulatingly supporting said windings from said core; a tubular casing surrounding said core and windings; metallic sheet material between said windings and said casing; a cap for said casing, said cap supporting the terminals for the coil; and means to secure said cap to said casing.

In testimony whereof, we affix our signatures.

WILLIAM G. SCHNEIDER.

HARRISON H. EATON.
